UNITED STATES PATENT OFFICE.

JOSEPH WILSON DEAN, JR., OF POND, MISSOURI, ASSIGNOR OF ONE-HALF TO J. WILSON DEAN, SR., OF POND, CENTAUR, MISSOURI.

VULCANIZER.

1,291,434.

Specification of Letters Patent. Patented Jan. 14, 1919.

Application filed October 22, 1917. Serial No. 197,841.

To all whom it may concern:

Be it known that I, JOSEPH W. DEAN, Jr., a citizen of the United States, and resident of Pond and State of Missouri, have invented certain new and useful Improvements in Vulcanizers, of which the following is a specification, containing a full, clear, and exact description, reference being had to the accompanying drawings, forming a part thereof.

My invention relates to new and useful improvements in vulcanizers, and has for its general object, the construction and application of a vulcanizer which is heated by the exhaust gases of a hydrocarbon engine. The further and special object of my invention is to equip the exhaust manifold of an engine with a vulcanizer and to have a vulcanizing apparatus ready for use as occasion may require.

In the drawings,

Figure 1 is a horizontal sectional view of my improved vulcanizer and a horizontal sectional view of the exhaust manifold of an engine with a part broken away showing partially in top plan view a portion of an engine.

Fig. 2 is a front elevation of the vulcanizer.

Fig. 3 is an end elevation of the vulcanizer applied to the exhaust manifold.

Fig. 4 is a transverse section taken on a line 2—2 of Fig. 2.

Fig. 5 is a top plan view of the vulcanizer illustrating an improved connection by means of which it may be applied to the exhaust manifold, part of the manifold being broken away.

Fig. 6 is a front elevation of the clamping clip employed in securing my vulcanizer to an exhaust manifold.

Fig. 7 is a transverse section taken on a line 6—6 of Fig. 6.

Referring to the drawings, 8 indicates a portion of an engine, 9 indicates the exhaust manifold thereof, and 10 indicates my improved vulcanizer which is cast or formed integral with the exhaust manifold 9, being connected thereto by a neck 11.

The vulcanizer is of rectangular shape, and is provided on the inside with deflecting plates or baffles 12, which extend from the ends of the vulcanizer inwardly, but are spaced apart in front of the neck 11, leaving a passage way 13.

It will be observed from Fig. 1 that the baffles 12 nearest the front of the vulcanizer project inwardly farther than the baffles 12 adjacent the neck 11.

Located in front of the passage way 13 is 60 a baffle 14. The purpose of the baffles 12 and 14 is to distribute the hot gases or heat within, and throughout the vulcanizer. The distribution of heat being shown by arrows in Fig. 1.

15 indicates screw plugs for closing the core openings. 16 indicates a thermometer which is arranged adjacent to the exterior wall of the vulcanizer for indicating the temperature of the same.

Cast on the rear of the vulcanizer are lugs or ears 17, provided with inclined slots 18, and cast on the front of the vulcanizer are catches or lugs 19. Mounted in the slots 18 is a rod 20, and mounted on the rod 20 is a 70 press frame 21. The press frame 21 being provided with perforated arms 22, in which is mounted the rod 20, and by this means the press frame 21 is hinged to the vulcanizer. The press frame 21 is provided 80 with depending arms 23, carrying hooked portions 24, which are adapted to engage with the hooks 19.

25 indicates a press plate, the same being countersunk as at 26, in which is located a 85 sheet of asbestos 27. Mounted in the press frame 21 is a screw 28 provided with a handle 29. The lower end of the screw 28 is mounted in the press frame 21 as illustrated in Fig. 4. The press plate 25 is carried by 90 the press frame 21. By the manipulation of the screw 28, the hooks 24 may be released from the hooks 19 by permitting the press frame to be lowered.

In the operation of vulcanizing the press 95 is clamped by means of the screw 28, which causes the press frame 21 to be elevated and the hooks 19 and 24 to engage. In this position sufficient clamping action may be applied as required.

In Figs. 1, 2, 3 and 4 I have shown my vulcanizer cast integral with the exhaust manifold 9, whereas in Figs. 5, 6 and 7 I have illustrated a construction by means of which the vulcanizer may be applied to the 105 exhaust manifold of engines already in use.

In order to attach the vulcanizer to an engine already in use, all that is necessary is to form a hole 30 in the exhaust manifold, and apply around the manifold the clip 31. 110

The clip 31 is provided with a screw threaded tubular extension 32 which tapers, and by means of an internally screw threaded coupling 33, the clip 31 may be secured on the manifold.

In this case when the vulcanizer is applied to an engine already in use, the neck 11 is provided with a screw threaded end 34, which is screw seated in the coupling 33.

10 This form of connection does not weaken the exhaust manifold and forms a tight joint preventing the escape of any of the hot gases.

15 Mounted in the neck 11 is a damper 35 for regulating the heat of the vulcanizer.

The vulcanizer may be attached at any position of the exhaust manifold, or even on the exhaust pipe, if desired.

20 It will thus be seen I have provided a vulcanizer for hydrocarbon engines, which is heated by the exhaust gases of the engine, and is carried by the engine, and always ready when the engine is in use, for vulcanizing purposes, no heating being required 25 except that derived from the hot gases of combustion from the engine. The vulcanizer is compact and being formed integral, it is air tight, preventing the escape of any of the gases. The baffles located on the inside 30 of the vulcanizer not only perform the function of distributing the heat, but also act to retain the heat, preventing the vulcanizer from cooling too quickly.

35 Having fully described my invention, what I claim is:

1. A vulcanizer for internal combustion engines cast integral and formed hollow, a series of baffle plates formed internally in the vulcanizer for distributing and holding 40 the heat, a connection for securing the vul-

canizer to and placing the same in communication with the exhaust manifold of an engine, a clamping frame pivotally secured to one side of the vulcanizer so that it is capable of bodily movement to and from the vulcanizer, and a press plate carried by said clamping frame.

2. A vulcanizer cast integral, and formed hollow, a series of baffle plates formed internally in the vulcanizer for distributing and holding the heat, a connection for securing the vulcanizer to and placing the same in communication with the exhaust manifold of an engine, a clamping frame pivotally mounted on one side of the vulcanizer so as to be bodily movable relative thereto, a press plate carried by said clamping frame, lugs carried by the vulcanizer, and lugs carried by the clamping frame adapted to engage therewith.

3. A vulcanizer cast integral and formed hollow, a series of baffle plates formed internally in the vulcanizer for distributing and retaining the heat, a connection for securing the vulcanizer to and placing the same in communication with the exhaust manifold of an engine, a clamping frame pivotally mounted on the vulcanizer on one side and provided on its opposite side with catches adapted to engage the vulcanizer, a press plate carried by said clamping frame, and a damper for regulating admission of heat to the vulcanizer.

In testimony whereof I have signed my name to this application in the presence of two subscribing witnesses.

JOSEPH WILSON DEAN, JR.
